(57) CLAIM

The ornamental design for an antenna for position detection,
as shown and described.

DESCRIPTION

FIG. 1 is a bottom, front and right side perspective view of
an antenna for position detection showing my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof, the left side
elevational view being a mirror image of the side view
shown; and,
FIG. 7 is a cross-sectional view thereof taken along line
7—7 in FIG. 2.
